UNITED STATES PATENT OFFICE

153,685

DESIGN FOR A HOSE NOZZLE

Andrew L. Henkel, Chicago, Ill.

Application February 12, 1947, Serial No. 136,864

Term of patent 7 years

(Cl. D62—2)

To all whom it may concern:

Be it known that I, Andrew L. Henkel, a citizen of the United States, residing at Chicago, Cook County, Illinois, have invented a new, original, and ornamental Design for a Hose Nozzle, of which the following is a specification, reference being had to the accompanying drawing, forming a part thereof.

This application is a continuation-in-part of applicant's copending application, Serial No. D-120,531, filed July 5, 1945, now abandoned.

Fig. 1 is a side elevation of a hose nozzle, showing my new design;

Fig. 2 is a front view of the hose nozzle shown in Fig. 1;

Fig. 3 is a rear view of the hose nozzle; and

Fig. 4 is a top view of the hose nozzle of my new design.

The stippling on the handle portion represents a contrast with the remaining areas.

I claim:
The ornamental design for a hose nozzle, substantially as shown and described.

ANDREW L. HENKEL.
